Inventor:
Frank Kusterle

By Fisher, Fawle, Clapp & Soans, Gtys.

UNITED STATES PATENT OFFICE.

FRANK KUSTERLE, OF KENOSHA, WISCONSIN, ASSIGNOR TO SIMMONS COMPANY, OF NEW YORK, N. Y., A CORPORATION OF DELAWARE.

ADJUSTABLE SUPPORT FOR BEDSPRINGS.

Application filed October 21, 1927. Serial No. 227,704.

This invention relates to adjustable supports for bed springs or other bed bottoms for facilitating mounting of the bed springs on a bedstead.

- 5 In bedsteads which include head and foot frames and side rails connecting the head and foot frames at opposite sides, the side rails are not always spaced apart the same distance. In metal bedsteads, the side rails 10 are often spaced apart a distance somewhat greater than the distance at which the corresponding parts of a wooden bedstead are spaced, and it is therefore desirable that some means be provided for enabling the bed 15 springs to be mounted on spaced side rails, the spacing of which may vary in different bedsteads.

The principal object of the present invention is, therefore, to provide an adjustable 20 supporting means connected to the bed springs for facilitating mounting of the bed spring on various bedsteads in which the distance between the side rails varies with each bedstead.

- 25 Other objects are to provide an adjustable supporting means which is adapted to be locked in operative position; to provide locking means which is operated or rendered effective by the weight of the bed spring when 30 mounted on the bedstead; to provide an adjustable support which will directly transmit the load of the bed spring to the side rail of the bedstead; to provide an adjustable support which is readily adjustable to the desired 35 position without the aid of tools or other devices; and in general, to provide an improved support of the class described.

Further objects and advantages of the invention will be understood by reference to 40 the following specification and accompanying drawings in which I have illustrated a selected embodiment of my invention in connection with a coiled spring type of bed spring and its manner of use for supporting the bed 45 spring on a metal bedstead and also a wooden bedstead.

In the drawings:

Fig. 1 is a cross section through a portion of a bed spring embodying my improved adjustable supporting means, and through an angle iron side rail of a metal bedstead.

Fig. 2 is a plan of a portion of Fig. 1.

Fig. 3 is a section corresponding to a portion of Fig. 1 but showing my improved support used for mounting the bed spring

on a wooden bedstead in which the side rails are closer together than the angle iron side rails of the bedstead contemplated in Fig. 1, and

Fig. 4 is a section on the line 4—4 of Fig. 3. Referring now to the drawings and more particularly, Fig. 1, I have shown a portion of a bed spring including an angle iron main frame portion 10, which constitutes one side of a generally rectangular frame which extends around the bed spring. Spring supporting slats, one of which is indicated at 11 and provided with upwardly extending end portions such as shown at 12 are secured to opposite side portions of the main frame by suitable means such as riveting, as indicated at 13. A plurality of coiled compression springs, a portion of one of which is shown at 14 are mounted on the spring supporting slats 11 and tied thereto in any suitable manner and are preferably anchored intermediate their top and bottom coils to intermediate coils of adjacent springs or to a stationary portion of the main frame as by means of helicals such as shown at 15. Border coil springs such as 16 are mounted on the horizontal portion 17 of the ends of the spring supports, and have their top coils connected to a border wire 18 in any suitable manner.

It has heretofore been common practice to mount the bed spring on a bedstead by placing the horizontal flange of the angle iron main frame directly on the top of the side rail of the bedstead. However, it has been found that in many bedsteads, particularly metal bedsteads, the side rails are spaced too far apart to permit such mounting. For overcoming this difficulty, I provide an adjustable support which in the present instance includes an arm 20 which is slidably mounted in a relatively long but narrow horizontally disposed slot 21 provided in the vertical flange 22 of the main frame and a part 23 which is secured to the outer end of the arm 20. The part 23 preferably consists of an angle iron member including a horizontal flange 24 which is adapted to engage the top of a side rail or as shown in Fig. 1, to engage the horizontal flange 25 of an angle iron side rail 26.

The angle iron part 23 is arranged so that its horizontal flange engages the horizontal flange of the side rail and also the under side of the horizontal flange 27 of the main frame

of the bed spring. It will thus be apparent that the load of the bed spring is transmitted directly through the angle iron part 23 to the side rail of the bedstead. The angle iron part 23 is prevented from turning upwardly about the outer edge of the horizontal flange 27 of the main frame by means of the arm 20 which is limited in its vertical movement adjacent its inner end by means of a bracket member 28 which is secured to the vertical flange 22 and provided with a slot 29 for receiving the inner end of the arm 20. The bracket 28 is preferably U-shaped, as best shown in Fig. 2 and is preferably secured to the vertical flange 22 by means of a pair of ears 30, which extend through suitable slots in the vertical flange and are then bent outwardly to lock the bracket in position. The inner end of the arm 20 is preferably notched as shown at 31 and the relatively narrow lug portions 32 and 33 are then bent in opposite directions as shown in Fig. 1 to prevent passage thereof through the slot 29.

For locking the arm 20 and the part 23 in the desired operative position, I provide the bar 20 with a plurality of notches or recesses 34 and 35 adjacent opposite edges thereof and the vertical flange 22 of the main frame with stops or ears 36 and 37 depending into the slot 21 from the upper edge thereof. When the part 23 is in operative position as shown in Fig. 1, that is, with its horizontal flange 24 engaging the horizontal flange of the main frame, the stops 36 and 37 enter the notches 34 and 35 respectively to thereby prevent movement of the arm 20 through the slot 21. It will be noted that when the parts are in the position shown in Fig. 1, there will be a tendency for the angle iron part 23 to turn upwardly about the outer edge of the horizontal flange 27 of the main frame, and that such turning is prevented by engagement of the inner end of the arm 20 with the lower edge of the slot 29 in the bracket 28. It will be apparent that when the weight of the bed spring is removed from the part 23 so that the arm 20 may move downwardly in the slot 21, the arm may then be moved through the slot to the desired position of adjustment and the stops 36 and 37 again brought into engagement with the desired recesses. As best shown in Fig. 2, the recesses are arranged in pairs, one being disposed opposite another on opposite edges of the arm.

In Fig. 3 I have shown the relative position of parts when the bed spring is mounted on a bedstead in which the supporting side rails are closer together than are the angle iron side rails contemplated in the illustration of Fig. 1. In the said Fig. 3, a wooden bedstead is contemplated and includes a side rail 38 having a supporting block or supporting rail 39 secured to its inner side for receiving and supporting the bed spring. As

shown in Fig. 3, the adjustable part 20 and 23 is moved to its inward limit of adjustment. In this instance, the vertical flange of the adjustable part 23 engages the ears 30 of the bracket 28 and is thereby prevented from further inward movement.

I have thus provided an adjustable support which readily permits mounting of the bed spring of which it forms a part, on bedsteads in which the spacing of the side rail differs. My improved supporting means is simple in construction, will not readily become damaged and inoperative and is capable of being easily and quickly adjusted and effectively locked in the desired position so that there is no danger of the bed spring slipping off the supporting rail of the bedstead.

The described details of my invention are merely illustrative of a single embodiment of my invention, wherefore the scope of the same should be determined by reference to the following claims which should be construed as broadly as possible, consistent with the state of the art.

I claim as my invention:

1. In combination, a bed spring having a main frame, a portion of which is provided with a horizontally disposed relatively long and narrow slot, a flat arm slidably mounted in said slot, having a pair of notches disposed in opposite edge portions, said arm being adapted adjacent its outer end to engage a portion of a bedstead for mounting the bed spring on said bedstead, and means for locking said arm against sliding movement in said slot when the bed spring is so mounted, comprising a pair of stops depending into said slot from the upper edge thereof at the ends of the slot, said stops being adapted to enter said notches, said slot being of sufficient vertical dimension to permit vertical movement of the arm in the slot relatively to the stops for disengaging said stops from said notches, thereby to permit adjustment of the arm.

2. In combination, a bed spring having a main frame, a portion of which is provided with a horizontally disposed relatively long and narrow slot, a flat arm slidably mounted in said slot and having a plurality of pairs of notches, the notches of each pair being located in oppositely disposed edge portions of said arm, said arm being adapted adjacent its outer end to engage a portion of a bedstead for mounting the bed spring on said bedstead, and means for preventing movement of said arm through said slot when the bed spring is so mounted comprising a pair of stops depending from the upper edge of said slot at the ends thereof, said stops being adapted to enter the respective pairs of notches in said arm, said slot being of sufficient vertical dimension to permit vertical movement of the arm in the slot relative to the stops for disengaging the notches from

the stops, thereby to permit adjustment of the arm inwardly or outwardly of the main frame through the slot.

3. In combination, a bed spring having an angle iron main frame, having its respective flanges disposed horizontally and vertically, the vertical flange depending from the inner edge of the horizontal flange and the latter being provided with a horizontally disposed, 10 relatively long and narrow slot, a flat arm slidably mounted in said slot, having oppositely disposed notches in its opposite edge portions, said arm being adapted adjacent its outer end to engage a portion of a bedstead 15 for mounting the bed spring thereon, a pair of stops carried by said main frame adjacent the ends of said slot for entering said notches to lock the arm against movement through the slot, and a bracket secured to said vertical flange and having a slotted portion spaced inwardly from said flange for slidably receiving and supporting the inner end of 20 said arm at such inwardly spaced point.
4. In combination, a bed spring having an angle iron main frame, the flanges of which are respectively horizontally and vertically disposed, the vertical flange depending from the inner edge of the horizontal flange, and provided with a relatively long and narrow 25 horizontally disposed slot, adjustable means for mounting the bed spring on a bedstead and comprising an arm slidably mounted in said slot and having a pair of notches respectively disposed in opposite edges thereof, a 30 substantially U-shaped bracket having its unconnected leg ends secured to said vertical flange and its leg-connecting bridge portion spaced inwardly from the vertical flange, said bridge portion being slotted for slidably 35 receiving the inner end portion of said arm, the latter having its inner end provided with a pair of lugs bent in opposite directions for preventing outward withdrawal of said arm from said slots, an angle iron part secured 40 to the outer end of said arm for engaging a portion of a bedstead and adapted to engage the under side of said horizontal flange, there-

by to support the bed spring on the bedstead, and means for locking said arm and part in predetermined position of adjustment comprising a pair of stops depending from the upper edge of said slot for entering said notches in said arm when the angle iron part engages said under side, said slot being of sufficient vertical dimension to permit vertical movement of the arm therein relative to said stops, thereby to disengage the stops from the notches in the arm for permitting adjustment of the latter inwardly or outwardly of the main frame. 60

5. In combination, a bed spring having a main frame including an angle iron member, the flanges of which are respectively horizontally and vertically disposed and the vertical flange of which depends from the inner edge of said horizontal flange and is provided with a relatively long and narrow horizontally disposed slot, an angle iron part having horizontal and vertical flanges, an arm slidably mounted in said slot, having 70 its outer end secured to the vertical flange of said part, the horizontal flange of said part being adapted to engage the under side of the horizontal flange of said angle iron frame member and to be seated on a portion of a 75 bedstead, thereby to support the bed spring on the bedstead, said arm being provided with a pair of oppositely disposed notches in its opposite edges, means for locking said arm against movement through said slot 80 comprising a pair of stops integral with the vertical flange of the main frame, depending into the slot from the upper edge thereof and adapted to enter the notches in said arm, said slot being of sufficient vertical dimension to permit vertical movement of the arm in the slot thereby to disengage the stops from the recesses and to permit movement of the arm through the slot, and a slotted bracket for slidably receiving and supporting 85 the arm at a point spaced inwardly from the vertical flange of said frame member. 90
